UNITED STATES PATENT OFFICE

142,068

DESIGN FOR AN EMBROIDERED TRIMMING OR THE LIKE

John Goldfrank, New York, N. Y.

Application May 26, 1945, Serial No. 119,742

Term of patent 3½ years

(Cl. D92—1)

To all whom it may concern:

Be it known that I, John Goldfrank, a citizen of the United States of America, residing in New York city, county of New York, and State of New York, have invented a new, original, and ornamental Design for an Embroidered Trimming or the like, of which the following is a specification, reference being had to the accompanying drawing, forming part thereof, wherein,

The figure is a plan view of an embroidered trimming or the like, showing my new design.

I claim:

The ornamental design for an embroidered trimming or the like, substantially as shown.

JOHN GOLDFRANK.
